TRAFFIC SIGNALING CONSTRUCTION

Filed Oct. 7, 1931

UNITED STATES PATENT OFFICE

JULIUS MATTSON, OF CHICAGO, ILLINOIS, ASSIGNOR OF ONE-FOURTH TO ERIC MATTSON
AND ONE-FOURTH TO HERMAN PALM, BOTH OF CHICAGO, ILLINOIS

TRAFFIC SIGNALING CONSTRUCTION

Application filed October 7, 1931. Serial No. 567,495.

My invention relates to improvements in traffic signaling constructions, and it consists in the combinations, constructions, and arrangements herein described and claimed.

5 An object of my invention is to provide a traffic signaling construction in which all of the signals may be transmitted by the light of a single lamp or group of lamps.

A further object is to provide a device of 10 the class described in which both the stop and go signals may be transmitted in any given direction through the same exterior window.

A further object is to provide a construction 15 of the class described which is provided with a stationary exterior casing in its upper portion in which a rotatably mounted interior casing may be moved horizontally in a predetermined manner.

20 A further object is to provide in a construction of the class described a rotatably mounted interior casing which is provided at its periphery with colored panes of glasses and is provided at its center with a common 25 source of light with which all of the panes are illuminated.

A further object of my invention is to provide 30 a construction having an inner revolving drum adapted to be operated intermittently and carrying a central lamp or group of lamps mounted on the drum.

35 A further object of my invention is to provide a means for displaying various shades of apparently rotating light which is adapted for use either as a toy or for advertising means.

40 A further object of my invention is to provide a device which is of cheap and simple construction, efficient in operation, and adapted to withstand long and continuous use.

45 Other objects and advantages will appear in the following specification, and the novel features of the invention will be particularly pointed out in the appended claims.

My invention is illustrated in the accompanying drawing, forming part of this application, in which

50 Figure 1 is an elevational view of a traffic

directing construction embodying my invention,

Figure 2 is a section taken along the line 2—2 of Figure 1,

Figure 3 is a section taken along the line 3—3 of Figure 2, and

Figure 4 is a section taken along the line 4—4 of Figure 2.

In carrying out my invention, I make use of a base 1, a tubular means 2 supported by the base, a supporting chamber 3, and an external housing 4 which encloses a rotatable housing 5. The external housing and the rotatable housing are each provided with a plurality of glass panes hereinafter to be described.

The base 1 may be provided at its bottom portion with a flange 6 which is perforated as indicated at 7 for the purpose of receiving bolts 8 by which the base may be rigidly secured to a cement block or other suitable object embedded in the ground or roadway. The base may be tapered outwardly, as indicated at 9, and may be provided with an internal bore 10 adapted to receive the sleeve 2. An opening 11 of sufficient size to pass electrical conductors may be provided just beneath the bore 10. The supporting chamber 3 may be provided with a reduced cylindrical base portion 12, the upper portion of which is flanged outwardly as is indicated at 13 and connected to a horizontal wall portion 14. The supporting chamber may also be provided with a roof portion 15 having a centrally disposed inwardly tapered collar portion 16. The collar portion is provided with a tapered bore 17 which is adapted to provide a bearing for a rotatably mounted shaft 18. All of the before-mentioned portions of the supporting chamber may, if desired, be formed integral- 20 ly with each other of a single piece of metal casting.

The sleeve 2 and the recessed portion 12 may be detachably connected together by any suitable means, such as the bolts 19. The reduced portion 12 may be provided with an internal bore 20 adapted to receive the shaft 18. If desired, a roller bearing means 21 and a cylindrical bearing 22 may be provided for the purpose of enabling the tapered shaft 18 to 100

rotate with a minimum of frictional losses. The tapered shaft 18, the roller bearing means 21, and the reduced cylindrical portion 12 may each be provided with central openings 23, 24, and 25, respectively, for the purpose of permitting the passage of electrical conductors to the lamp 26. The upper portion of the tapered shaft 18 may be provided with a recessed portion 27 of such a size as to permit the socket of a lamp to be suitably mounted therein, together with a rotatable switch, not shown.

The electrical conductors may, if desired, be encased in an insulated tubing. The rotatable switch may be operatively connected to the socket 28 in any suitable manner adapted to permit the lamp 26 to rotate and yet remain in connection with the electrical conductors. If desired, the upper tapered portion 29 of the shaft 18 and the collar 16 of the supporting chamber 3 may be sufficiently enlarged to enable the recess 27 to receive a plurality of lamps which may, if desired, be substituted for the one lamp 26.

The supporting chamber may be provided with a door 30 which may be swingingly carried by hinges 31 secured to the cylindrical chamber wall 14. The base of the exterior housing 4 may be formed of a saucer-shaped member 33 having a centrally disposed opening which is adapted to fit snugly about the upper cylindrical portion of the collar 16, substantially as shown.

The roof portion 15 of the supporting chamber may be flanged as is indicated at 32. The saucer-shaped member 33 may be rigidly secured to the top portion 15 by means of bolts 35. The member 33 may be also provided with a peripheral downwardly and outwardly extending flanged portion 36 adapted to support, a cylindrical wall portion 37 of the exterior housing 4. The flanged portion 36 and the wall portion 37 may be rigidly secured together by welding or by any other suitable means, such as, for instance, by the bolts 38. The wall portion 37 may be provided with a plurality of oppositely disposed openings 39. These openings may be provided with window frames 40 adapted to carry a plurality of glass panes 41. The window frames 40 may be rigidly secured to the wall portion 37 and a peripheral flange 42 of a dome-shaped cover portion 43 by means of bolts 44. The cover portion 43 may be provided at its upper central portion with an opening 45 adapted to receive a cap member 46.

The cap member 46 may be provided with a rod 47 having a knurled head 48 by which the cap portion may be removed for the purpose of obtaining access to the interior of the housing 5. The cap member 46 and the cover portion 43 may be provided with means, not shown, whereby the cap may be locked to the housing 5.

The upper portion 29 of the shaft 18 may

be provided with shoulders 49, a reduced threaded portion 50, and a nut 51 for the purpose of supporting and retaining a saucer-shaped base member 52 which is provided with a central opening. The saucer-shaped member 33 and the saucer-shaped base portion 52 may each be provided with a plurality of openings 53 for the purpose of admitting air into the interior housing 5. The member 52 may be provided with a horizontally disposed rim portion 54 and a downwardly and outwardly flanged portion 55. The interior housing 5 is also provided with an outwardly and downwardly inclined cover portion 56. The cover portion 56 is provided at its top with an upwardly extending collar member 57 adapted to receive a cap member 58. The cap member 58 may be depressed in its central portion and provided with a handle 59. The cap members 46 and 58, when removed, provide means of obtaining access into the interior of the housing 5 for the purpose of providing a new lamp when one is needed and for cleaning, if necessary, the interior of the housings 4 and 5. The cover portion 56 is provided with a horizontally extending rim portion 60 and an upwardly and outwardly flanged portion 61.

The horizontal rim portion 54 of the base member 52 and the rim portion 60 of the cover portion 56 are each provided with a plurality of openings 62 for the purpose of receiving a bolt means 63. Each of the bolt means 63 is provided with a flat inner end portion 64.

The flat end portions 64 of the bolt means 63 are adapted to cooperate with the flanged portions 55 and 61 in detachably securing a plurality of curved colored panes of glass 65 to 72, inclusive. Each of these panes is provided at its upper and lower portions with an inwardly extending flange 73.

From the foregoing description of the various parts of the device, the operation thereof may be readily understood. Now let us assume for the purpose of illustration that the glass panes 65 and 69 are green, that the panes 67 and 71 are red, that the intermediate panes 66, 68, 70, and 72 are yellow, that the panes are in the position indicated in Figure 3, and that the lamp 26 is lighted.

The traffic facing the green lights is of course being given the right of way, while the traffic facing the red lights is stopped. The interior housing may now be slowly and steadily rotated until the yellow panes are advanced to such a position that only a yellow light will shine through the windows 41. The housing may then be rapidly rotated in the same direction until the red and green lights have exchanged their former positions. During the interval during which the yellow panes are slowly and steadily coming into view, the people on both of the inter-

secting streets will be enabled to determine at any instant from the position of the yellow panes approximately how much time will elapse before the change in the position of the red and green lights is fully made.

5 This ability to determine the amount of time elapsing before the complete change of traffic signals is completed will prove of value both to the pedestrian and the automobilist. It is particularly necessary for the infirm 10 pedestrian to be able to determine whether or not he can cross the street before the on-rush of the automobiles incidental to a change in traffic signals.

15 The fact that the information is conveyed to a pedestrian by the light of a single lamp through a single window tends to prevent confusion and to eliminate accidents as it is an extremely simple thing to watch a single window.

20 It will of course be understood that the window panes 41 may be made in any suitable size or shape and that the rotatable housing 5 may be moved in either a clockwise or 25 counterclockwise direction. If desired, an opening 75 may be provided extending through the reduced cylindrical base portion 12 of the supporting chamber 3 for the purpose of admitting electrical conductors to the motor and the timing mechanism where- 30 by the shaft 18 and the interior housing 5 is actuated. The supporting chamber may be of a suitable size to receive these electrical elements.

35 While I have shown the supporting chamber 3 and the stationary and rotatable housing supported by the base 1 and the tubular means 2, it will be understood that these may be supported in any other suitable manner and may, if desired, be secured to a bridge or 40 any other suitable platform above the street.

45 The device of my invention as shown in Figure 1 may be made, if desired, in miniature for the purpose of providing toys for children or display means for advertising purposes.

I claim:

50 1. In a signaling device of the character described, the combination of a rigid hollow supporting housing, an external housing rigidly secured to and carried on the top of said supporting housing, a rotatable chamber rotatably mounted within the external housing and being provided with a down- 55 wardly extending tubular shaft, rotatably carried by said supporting housing and threaded means in the upper end of said shaft whereby an electric bulb may be thread- 60 edly carried in said shaft, and extending di- rectly above said shaft, said housing and said chamber each being provided with top, bot- 65 tom and side walls, the side walls of said housing being provided with a plurality of oppositely disposed windows, the side walls 70 of said chamber being transparent and con-

sisting of a plurality of pairs of colored panes, each pane of said pairs being of the same color, and being oppositely disposed with respect to each other.

2. In a signaling device of the character de- 70 scribed, the combination of a rigid hollow supporting housing, an external housing rigidly secured to and carried on the top of said supporting housing, a rotatable chamber rotatably mounted within the external 75 housing and being provided with a downwardly extending tubular shaft, rotatably carried by said supporting housing and threaded means in the upper end of said shaft whereby an electric bulb may be threadedly 80 carried in said shaft, and extending directly above said shaft, said housing and said chamber each being provided with top, bottom and side walls, the side walls of said housing being provided with a plurality of oppositely 85 disposed windows, the side walls of said chamber being transparent and consisting of a plurality of pairs of colored panes, each pane of said pairs being of the same color, and being oppositely disposed with respect to each other, each of said plurality of colored panes being provided with flanges whereby 90 said plurality of panes may be clampingly bolted to the top and bottom walls of said housing. 95

3. In a signaling device of the character described, the combination of a rigid hollow supporting housing, an external housing rigidly secured to and carried on the top of said supporting housing, a rotatable chamber rotatably mounted within the external housing and being provided with a downwardly extending tubular shaft, rotatably carried by said supporting housing and threaded means in the upper end of said shaft whereby an electric bulb may be threadedly 100 carried in said shaft, and extending directly above said shaft, said housing and said chamber each being provided with top, bot- 105 tom and side walls, the side walls of said housing being provided with a plurality of oppositely disposed windows, the side walls of said chamber being transparent and consisting of a plurality of pairs of colored panes, each pane of said pairs being of the same color, and being oppositely disposed with respect to each other, the top walls of said housing and said chamber being each provided with central openings and means for closing 110 said openings whereby access may be had to the interior of the housing and the chamber, and said openings may be thereafter closed in a water tight manner. 115

4. In a signaling device of the character described, the combination of a rigid hollow supporting housing, an external housing rigidly secured to and carried on the top of said supporting housing, a rotatable chamber rotatably mounted within the external 125 housing and being provided with a down- 130

wardly extending tubular shaft, rotatably carried by said supporting housing and threaded means in the upper end of said shaft whereby an electric bulb may be threadedly carried in said shaft, and extending directly above said shaft, said housing and said chamber each being provided with top, bottom and side walls, the side walls of said housing being provided with a plurality of oppositely disposed windows, the side walls of said chamber being transparent and consisting of a plurality of pairs of colored panes, each pane of said pairs being of the same color, and being oppositely disposed with respect to each other, each of said plurality of colored panes being provided with flanges whereby said plurality of panes may be clampingly bolted to the top and bottom walls of said housing, the top walls of said housing and said chamber being each provided with central openings and means for closing said openings whereby access may be had to the interior of the housing and the chamber, and said openings may be thereafter closed in a water tight manner.

5. In a signaling device of the character described, the combination of a supporting housing and an external housing rigidly secured to and carried on the top of said supporting housing, and a rotatable chamber rotatably mounted within said external housing, said external housing and said rotatable chamber each being provided with top, bottom and side wall portions, the side wall portions of said external housing being provided with transparent windows, the side wall portion of said rotatable housing comprising a plurality of colored panes, each of said panes being provided with end portions, the end portions of each of said panes contacting and being in alignment with the end portions of an adjacent pane so as to provide a side wall which is entirely transparent.

Signed at Chicago, in the county of Cook, and State of Illinois, this 24th day of September, A. D. 1931.

JULIUS MATTSON.
